UNITED STATES PATENT OFFICE.

MANDEVILLE THUM, OF LOUISVILLE, KENTUCKY.

SAFETY CUT-OUT.

SPECIFICATION forming part of Letters Patent No. 472,084, dated April 5, 1892.

Application filed June 5, 1891. Serial No. 395,269. (No model.)

To all whom it may concern:

Be it known that I, MANDEVILLE THUM, a citizen of the United States, residing at Louisville, in the county of Jefferson and State of Kentucky, have invented certain new and useful Improvements in Apparatus for Insuring and Increasing the Safety of Electric Circuits or Conductors, of which the following is a specification.

10 The object of the improvement is to insure or enhance the safety of electric circuits or conductors, especially those which are used for electric lighting, railway, or power purposes. This I accomplish by guarding them 15 in such manner that a signal is given or that a change in the circuit—such as a break, a decrease of its conductive capacity, or the substitution for the whole or a part of it of other conducting devices—is automatically 20 effected upon the occurrence of an accident—such as the breaking of a conductor of the guarded circuit or the crossing of it by another conductor—or upon the occurrence of other conditions which render such change 25 desirable, but which may not come within the term "accident."

To this end my invention consists in the combination, with a main circuit or circuit to be guarded, of a safety device comprising a 30 branch circuit connected with said guarded circuit and an electro-mechanical device of suitable character in a branch circuit and adapted to operate to change the guarded circuit upon a change of the current in the latter.

35 My invention further consists in the parts and combinations thereof hereinafter particularly set forth and claimed.

In order to make my invention more clearly understood, I have shown in the accompanying drawing means for carrying the same into effect without, however, limiting the improvement in its application to the particular construction which, for the sake of illustration, I have delineated.

40 In said drawing the figure is a diagram of an electric circuit and safety device embodying my invention.

Referring to the drawing, A indicates the conductor to be guarded, which may be that of

an electric railway, a lighting-circuit, power- 50 circuit, or other electric conductor. G is the generator or source of electric energy for said circuit.

S is a safety device comprising a branch circuit a, connected with the main conductor 55 A, and having therein a thermo-electrical instrument, galvanometer, electro-magnet, or other electro-mechanical device. In the drawing the latter is shown as an electro-magnet at M, through the helix of which the circuit 60 a passes. L is the armature-lever for said magnet, carrying or operating an electric contact P, adapted to engage or be separated from a contact P'. These contacts are in and form the means of completing the circuit A. The 65 branch circuit a is also provided with electric contacts p p', which are adapted to be operated by a second electro-mechanical device, such as a magnet M' and armature-lever L', the latter carrying the contact p and the 70 former having its helix in the circuit A. The parts are arranged so that the attractive force of the magnet M' will maintain a separation of the contacts pp'. If now a break occur in the line A, such separation will cease, the circuit 75 a will be completed, and magnet M energized, and the circuit A will be positively and forcibly broken at P P' by the operation of said magnet and its lever L. So much of the current from circuit A may be admitted 80 to the circuit a as is desirable, a suitable resistance or resistances being employed.

What I claim is—

In a safety device for electric circuits, the combination, with the main circuit, of a 85 branch circuit, an electro-mechanical device therein, electric contacts in the main circuit adapted to be operated by said electro-mechanical device, contacts in the branch circuit, and an electro-mechanical device in the 90 main circuit and adapted to control the latter contacts, substantially as set forth.

In testimony whereof I hereunto set my hand in the presence of two witnesses.

MANDEVILLE THUM.

Witnesses:

H. N. LOW,

WILLIAM L. ALLEN.
